UNITED STATES PATENT OFFICE

153,399

DESIGN FOR A GRAVE MARKER

Donald Spencer, Ironton, Ohio, and
Max H. Spencer, Moline, Ill.

Application April 9, 1947, Serial No. 138,260

Term of patent 7 years

(Cl. D79—2)

To all whom it may concern:

Be it known that we, Donald Spencer and Max H. Spencer, citizens of the United States, residing at Ironton and Moline, respectively, in the counties of Lawrence and Rock Island, respectively, and States of Ohio and Illinois, respectively, have invented a new, original, and ornamental Design for a Grave Marker, of which the following is a specification, reference being had to the accompanying drawing, forming part thereof.

Figure 1 is a front elevational view of a grave marker, showing our new design,
Figure 2 is a side elevational view thereof, and
Figure 3 is a rear elevational view thereof.

We claim:

The ornamental design for a grave marker, as shown.

DONALD SPENCER.
MAX H. SPENCER.
